FIG. 2.

FIG. 3.

UNITED STATES PATENT OFFICE.

LOUIS W. LABOFISH, OF WASHINGTON, DISTRICT OF COLUMBIA, ASSIGNOR TO UNION TYPEWRITER COMPANY, OF ILLION, NEW YORK, A CORPORATION OF NEW YORK.

TYPE-WRITING MACHINE.

1,000,019.

Specification of Letters Patent.

Patented Aug. 8, 1911.

Application filed May 12, 1910. Serial No. 560,838.

To all whom it may concern:

Be it known that I, LOUIS W. LABOFISH, citizen of the United States, and resident of Brightwood Park, city of Washington, District of Columbia, have invented certain new and useful Improvements in Type-Writing Machines, of which the following is a specification.

My invention relates to typewriting machines and more particularly to means for maintaining a fixed relation between anti-friction rollers for supporting the carriage and for maintaining a proper relation between said rollers and the carriage and between the rollers and the frame of the machine during the travel of the carriage.

The main object of my invention is to provide simple, efficient and inexpensive means of the character specified.

20 A further object of my invention is to provide means of the character specified which may be readily applied to existing forms of typewriting machines without altering the structural features of said machines as they now exist.

To the above and other ends which will hereinafter appear, my invention consists in the features of construction, arrangements of parts and combinations of devices 30 to be hereinafter described and particularly pointed out in the appended claim.

In the accompanying drawings wherein like reference characters indicate corresponding parts in the various views, Figure 35 1 is a fragmentary vertical fore and aft sectional view showing so much of one form of typewriting machine as is necessary to illustrate my invention in its embodiment therein. Fig. 2 is a fragmentary bottom view 40 showing portions of the carriage and its supporting means, together with the means for controlling the position of the anti-friction rollers. Fig. 3 is a detail rear view of the anti-friction rollers and the separator therefor, together with a pinion carried by said separator. Fig. 4 is an enlarged detail 45 transverse sectional view taken through the front carriage trucks.

I have shown my invention applied in the 50 present instance to a No. 10 Remington machine in which the invention may be readily embodied without changing the structural features of said machine as they now exist. It should be understood, however, that the

invention may be embodied in other styles 55 of typewriting machines.

The corner posts 1 of the machine support a top plate 2 from which upwardly extending lugs 3 project. Front and rear fixed carriage tracks or rails 4 are supported on 60 the lugs 3 and have grooved faces, as indicated at 5, for the reception of and coöperation with anti-friction rollers 6 and 7. The rollers 6 and 7 for each of these tracks turn on pivots 8 and 9 respectively which are arranged at substantially right angles to each other, the pivots 9 being received in sheet metal arms 10 of a roll holder or separator. The planes of the arms 10 are substantially 65 at right angles to the planes of the pivot receiving arms 11 formed integral with the arms 10. The arms 11 are riveted at 12 to parallel plates 13 which, together with the arms 10 and 11, constitute a roll holder or separator for maintaining the rollers in 70 fixed relation one to another. A pair of crossed anti-friction rollers 6 and 7 are provided at each end to the roller separator as shown in Fig. 3. The rollers 6 and 7 co-operate with front and rear rails or tracks 75 14 formed on front and rear cross bars of a carriage 15. The tracks 14 are grooved at 16 for the reception of and coöperation with the anti-friction rollers 6 and 7. The anti-friction rollers thus support the carriage 80 and guide it in its movement from side to side of the machine over the top plate. Each roller separator has a block 17 interposed between the parallel plates 13 and secured thereto by rivets 18. A vertically disposed opening is drilled through each block 17 and through the edge of one of the parallel plates 13 for the reception of a spindle 19, riveted or headed at 20, to rigidly connect the spindle with the roller separator. 85 Each spindle 19 extends downwardly from its roller separator through the space provided between the associated tracks 4 and 14. A pinion 21 is mounted to turn freely 90 on each spindle 19 and is supported in place by the lower headed end 22 of the spindle. The effective diameter of each pinion 21 is 95 shown in the present instance as about the same diameter as the anti-friction rollers 6 and 7, although the diameter of the pinions may be varied at will. Pinions of about 100 the size of those shown in the present instance lend themselves readily to embodi- 105

ment in the No. 10 Remington machine. Racks 23 are fixed by screws 24 to the bottom of the fixed tracks 4 and are each arranged to mesh with the associated pinion 21 on one side thereof. Oppositely disposed racks 25 are fixed to the tracks 14 on the carriage by screws 26, the teeth of each rack 25 engaging with the associated pinion 21 on the side thereof opposite the companion rack 23.

The construction and arrangement of the parts are such that a movement of the carriage will produce a relative movement between the racks 25 and 23 and the engagement between these racks and the pinions 21 will cause the pinions to travel one half the distance of the carriage in its movement from side to side of the machine and to produce a corresponding movement of the roller separators and the anti-friction rollers carried thereby. The construction is therefore effective to prevent an undue displacement of the anti-friction rollers 6 and 7 and to maintain a fixed relation between said rollers and the carriage, and between said rollers and the fixed frame of the machine at any given point in the travel of the carriage. That is to say, when the carriage is centrally positioned on the frame, for example, as shown in Fig. 2, then the rollers for each companion pair of tracks will be in the positions shown relatively to the carriage and relatively to the frame, and these positions of the rollers will always be the same when the carriage is centered.

When I refer herein to anti-friction "rollers," this term is used in a broad sense and is intended to apply to such rollers, whatever may be the shape thereof.

The carriage and the manner of supporting and guiding it is the same as the con-

struction usually embodied in the No. 10 Remington machine, although the platen 27 is merely conventionally shown in Fig. 1. It will be understood that it is merely necessary to add the spindles 19, pinions 21 and racks 23 and 25 to the ordinary equipment of the No. 10 Remington machine in order to embody my invention in such machine, and that I have provided simple and efficient means for maintaining the proper relation between the anti-friction rollers and the frame of the machine and carriage.

What I claim as new and desire to secure by Letters Patent, is:—

In a typewriting machine, the combination of a carriage; a grooved track carried by the carriage, a grooved track carried by the frame of the machine, said tracks being spaced apart horizontally, anti-friction carriage supporting rollers in said grooved tracks, a separator comprising parallel plates between which said rollers are received and to which they are pivoted to maintain a fixed relation between the rollers, a block between and secured to the parallel plates of the separator, a spindle mounted in said block and passing through the space between said tracks, a pinion carried by said spindle, a rack fixed to the carriage and co-operative with said pinion on one side thereof, and a second rack fixed to the frame of the machine and co-operative with said pinion on the opposite side thereof.

Signed at city of Washington, District of Columbia, this 9th day of May, A. D. 1910.

LOUIS W. LABOFISH.
